UNITED STATES PATENT OFFICE

WINFRED M. BROOKS, OF WEST ORANGE, NEW JERSEY

SEALING MEANS

Application filed October 17, 1928. Serial No. 313,031.

This invention relates to shackle-seals and has for its main object and feature the production of a seal of simple construction and capable of resisting relatively great force 5 without becoming unsealed.

In the accompanying drawings the invention is disclosed in a concrete and preferred form in which:

Fig. 1 is a plan view of a sealing means embodying the invention;

Fig. 2 is an edge view of the parts shown in Fig. 1;

Fig. 3 shows the shackle bent back upon itself with the nested cup-shaped portions 15 shown in section, but before compression; and

Fig. 4 is a detail sectional view with the cup-shape portions as they appear after compression.

1 indicates a shackle, here of sheet material, 20 having integrally formed therewith two cup-shape portions 2 and 3, in the present instance located at opposite ends.

It will be observed that portion 2 is of greater diameter and shallower than portion 25 3, and that the latter is of lesser diameter but deeper than portion 2. These portions are nested after the manner shown in Fig. 3, by bending the shackle back upon itself and inserting portion 3 within portion 2. It will 30 be apparent that portion 2 must be slightly larger in diameter than 3, but heretofore it has been the practice to make the portions of substantially the same depth. I find that by making portion 3 considerably deeper than 2, 35 that, when the parts are compressed by a punch as in Fig. 4, a very intimate engagement of the metallic layers takes place, by reason of the excess of metal in portion 3, and that it is exceedingly difficult to there- 40 after separate the parts. If desired, a weakened zone or opening 4 is located between each portion 2 or 3 and the main body of the shackle member which renders it practically impossible to obtain a purchase adjacent 45 members 2 and 3, sufficient to separate the parts.

I prefer to initially provide portion 2 with a slightly dished top as indicated at 5 in Fig. 3, as it seems to assist in spreading the 50 metal after the manner shown in Fig. 4, when

compression is applied to the parts by means of a smooth-faced tool.

I claim:

Sealing means including: a shackle member, and two cup-shape sheet material portions, having closed bottoms, to nest one within the other and to be thereafter sealed by compression, the outer one of said nested portions being of greater diameter and shallower than the inner one, and said inner portion being of lesser diameter and deeper than the outer one.

Signed at New York, in the borough of Manhattan, county and State of New York, this 10th day of October, 1928.

WINFRED M. BROOKS.
